UNITED STATES PATENT OFFICE.

JAMES K. WHITE, OF MANSFIELD, OHIO.

GRAIN-SEPARATOR.

SPECIFICATION forming part of Letters Patent No. 783,603, dated February 28, 1905.

Application filed March 18, 1904. Serial No. 198,726.

To all whom it may concern:

Be it known that I, JAMES K. WHITE, a citizen of the United States, and a resident of Mansfield, Richland county, State of Ohio, have invented certain new and useful Improvements in Grain-Separators; and my preferred manner of carrying out the invention is set forth in the following full, clear, and exact description, terminating with claims particularly specifying the novelty.

This invention relates to threshing, and more especially to those machines employed in the art which are known as "separators," and the object of the same is to separate the straw from the chaff and the chaff from the grain by rotary mechanism in a more effective manner than hitherto.

To this end the invention consists in a separator shaped practically like an inverted umbrella and employing in its separating mechanism the combined force of centrifugal power and of suction simultaneously produced by the rotation of a single element.

To this end the invention consists in a machine constructed substantially as hereinafter described and claimed and as set forth in the drawings, wherein—

Figure I is a central vertical section of this separator complete. Fig. II is a side view of the same. Fig. III is a plan view showing portions of the top of the casing broken away. Fig. IV is a side view, and Fig. V a plan view, of the rotating element.

In the drawings the numeral 1 designates a framework supporting a casing, whose fixed body 2 is shaped like an inverted cone and whose top 3 (preferably removable to permit access to the interior of the machine) is shaped like a truncated cone or large ring cut radially at one point and sprung out of its plane to produce the exit, the side wall of the body at its upper edge being shaped to conform with the outer edge of this ring and assist in producing said exit for a purpose to appear below. Fixed within and depending from said top is a hopper 4, whose walls converge downward from the inner edge of said ring to a large circular mouth 5. Beneath the higher end of said ring-top 3 at the point of exit, as

shown in Fig. III, are located two upright partitions 6, which divide the exit into three channels at radially different distances from the center; and the object of the present invention is to feed out of the outermost exit 50 the waste grain, out of the intermediate exit 55 the chaff, and out of the innermost exit the straw, the cleaned grain being meanwhile delivered at the lower end of the machine, as set forth below.

The rotating element of this separator is 60 shown in several views. An upright shaft 10 is mounted in a suitable bearing or step 11 in the framework 1 and is driven by power applied at any suitable point either above or below. Within the casing, about midway of 65 its height, there is fixed upon its shaft a spider 12, whose radiating arms support the chaff hopper or tube 13, which concentrically surrounds the shaft, is preferably cylindrical, and is furthermore connected therewith by an interior spiral plate or strip 14, whose convolutions are pitched in such direction that in the rotation of this member it will produce a downward suction through said hopper or tube. It will be obvious that chaff and grain fed into 70 this tube and drawn downward by the spiral will be delivered through said spider 12 and (if there were no other force applied to it) would fall downward within the conical casing 2 and drop out its lower end or mouth 15 75 in an unseparated condition, and for the purpose of producing the separation of these elements, as well as to remove the longer straw which is usually fed into the machine, I provide the following additional devices: 80

Carried, preferably, by the rotating hopper 13 are a series of fan-blades 20, preferably standing in vertical planes and preferably tangential to the hopper, with their outer ends inclined forward toward the direction in which 85 they will rotate, whereby in operation they cut or churn through the material which is dropped through the main hopper 4.

21 is a ring connecting and bracing the outer ends of these blades, and the walls of 90 this ring diverge downward about parallel with and slightly remote from the walls of the body 2, the space between these members

being sufficient to cause them to clear each other. Standing nearly horizontal within the rotating element and cutting through these fan-blades near their upper edges is what I 5 will call a "partition" 22. It is of ring shape, its inner edge forming a circle surrounding and somewhat larger than the diameter of the chaff-hopper 13 and its outer edge (which is possibly elevated slightly) alining quite accurately 10 with the inner partition 6 in the outlet through the casing-top 3. The function of this rotating partition is to separate the straw from the chaff and grain and cause the former to pass out of the straw-outlet. It is obvious 15 that when the material to be separated is fed in through the main hopper 4 the grain and some of the chaff will be sucked down by the inner spiral 14 through the chaff-hopper 13, while the straw and the longer chaff will be 20 caught by the upper edges of the fan-blades, and by the centrifugal force thus imparted will be thrown outward over the partition and driven out the straw-exit. It therefore remains only to separate the chaff from the grain. 25 Cutting through the fan-blades beneath the partition above described is an outer spiral plate or strip 30, which I call a "spiral" because its convolutions are pitched in a direction to produce an upward suction within the 30 ring 21. These convolutions are shown as individually inclined outward and downward, although individually they might be horizontal; but it is desirable that the general plane of the inner convolution shall be lower and those 35 outside of it respectively higher and higher as they approach the interior of the ring, and, moreover, the convolutions should lap joint with each other slightly. The effect of this detail of construction when the rotating element 40 is rapidly revolved is to set up an upward suction within the ring and beneath the partition, and hence the chaff and grain which has been sucked down through the chaff-hopper is immediately sucked upward and outward by the 45 outer spiral. Passing up within the ring 21 the kernels of the grain are struck by the convolutions of the outer spiral and thrown outward against said ring, this action being enhanced by the greater weight of said kernels, 50 and the result is that the waste grain will pass out the waste-grain exit in the casing-top 3, while the chaff will pass out the intermediate exit therein. 55 The fact that the outer spiral revolves in a larger circle than the inner will cause it to rotate at a greater speed though driven by the same shaft, and hence there will be a greater upward suction outside of the chaff-hopper than there is a downward suction within it. 60 The result will be an upward draft of air through the mouth 15, and against the force of this draft almost absolutely nothing but cleaned kernels of grain will fall. Provision may be made for a damper 150 to more or less close this mouth, if desired. Under some

circumstances also it may be desirable to place a ring-shaped partition 160 within the body 2 beneath the spider and closely around the shaft which supports the chaff-hopper, and the presence of this ring bottom will check 70 and deflect upward the downwardly-passing chaff and grain. I have also shown in the drawings a feature which may possibly be dispensed with. This consists of a number of tines 170 radiating from the hopper 13, 75 preferably bent upward and rotating within the main hopper 4, their purpose being to break up the long straw which is fed thereinto.

In operation the machine is set up, a bag or clean-grain receptacle placed beneath the 80 mouth 15, and chutes connected with the three side outlets, after which rotary motion is imparted to the main shaft 10. The material to be separated is thrown into the hopper 4, around and outside of the shaft-hopper 13. 85 If the tines 170 are employed, this material is immediately broken up and given a whirling motion, and the suction produced by the inner spiral assists this motion in drawing the material downward through the mouth 5 90 upon the rotating element. Here the upper edges of the fan-blades catch the broken-up straw and impart to it a radial motion, and the centrifugal force thus set up drives it out over the partition 22 and finally passes it out 95 the straw-exit. Meanwhile the chaff and grain drop through the fan-blades, (and the chaff and grain which have been fed into the chaff-hopper for recleaning drop through the spider,) and the upward suction produced by 100 the outer spiral draws them upward and outward assisted by centrifugal force. The latter acts strongest upon the particles which are heaviest, and hence the grain is more likely to slide up the inner face of the ring 105 21, and in addition such kernels as are struck by the outer spiral are forcibly thrown against such face, the result being that most of the kernels are driven out of the waste-grain exit. Meanwhile the lighter particles of chaff are 110 carried around and upward and outward by the same forces and pass out the chaff-exit. Finally, only those kernels which have been thoroughly cleansed will drop through the funnel-shaped body 2 and out the mouth 15 115 against the inrush of air through that mouth, which is produced by the rotation of the outer spiral, and even this may be avoided by inserting the removable bottom 160, for the careful operator generally recleans the grain 120 which passes out the waste-exit. This will be done by returning it to the machine and feeding it into the chaff-hopper 13, as above mentioned.

I have refrained from stating the sizes, 125 shapes, proportions, and materials of parts because they are not important to the successful operation of the machine. It is also obvious that changes in details and omission and substitution of features can be indulged 130

in to a considerable extent without departing from the spirit of my invention. It may not be necessary to employ both spirals in one machine. It is possible that the partition 5 might be omitted. As stated above, the tines are only sometimes employed, and various other changes in detail will suggest themselves to the practical operator.

What is claimed as new is—

10 1. In a grain-separator, the combination with a casing comprising a body and a top, the latter being a ring cut radially with its ends sprung out of register to form an exit, and a main-hopper opening through said top; of a 15 rotating element mounted on a central vertical shaft within the casing and carrying a series of substantially upright fan-blades, and a spiral plate connected with the blades and rotated by the shaft for producing an upward and outward 20 suction within the casing remote from said shaft.

2. In a grain-separator, the combination with a casing comprising a body and a top, the latter being a ring cut radially with its ends 25 sprung out of register to form an exit, and a main-hopper opening through said top; of a rotating element mounted on a central vertical shaft within the casing and carrying a series of substantially upright fan-blades, and two 30 spiral plates for producing a downward suction immediately around said shaft and an upward and outward suction within the casing remote from the shaft, said plates being connected with the blades at different distances from the 35 shaft and rotated bodily by the latter.

3. In a grain-separator, the combination with a casing comprising a body and a top, the latter being a ring cut radially with its ends sprung out of register to form an exit, and a 40 main-hopper opening through said top; of a rotating element mounted on a central vertical shaft within the casing and carrying a series of substantially upright fan-blades, a tubular chaff-hopper surrounding said shaft, and 45 means for producing a downward suction within such hopper.

4. In a grain-separator, the combination with a casing comprising a body and a top, the latter being a ring cut radially with its ends 50 sprung out of register to form an exit, and a main-hopper opening through said top; of a rotating element mounted on a central vertical shaft within the casing and carrying a series of substantially upright fan-blades, a tubular chaff-hopper surrounding said shaft, means 55 for producing a downward suction within such hopper, and means for simultaneously producing an upward and outward suction exterior of this hopper.

60 5. In a grain-separator, the combination with a casing having a plurality of tangential exits, and a main hopper; of an upright shaft journaled through the axis of the casing, upright fan-blades carried by the shaft, a ring 65 uniting the outer ends of said blades and ro-

tating within the casing, and a spiral carried by the blades and pitched to create an upward suction.

6. In a grain-separator, the combination with a casing having a plurality of tangential 70 exits, and a main hopper; of an upright shaft journaled through the axis of the casing, upright fan-blades carried by the shaft, a ring uniting the outer ends of said blades and rotating within the casing, a spiral plate carried 75 by the blades and pitched to create an upward suction, the inner convolution of said spiral plate being lowest and its outer convolutions successively higher and higher, for the purpose set forth.

7. In a grain-separator, the combination with a casing having a plurality of tangential exits, and a main hopper; of an upright shaft journaled through the axis of the casing, upright fan-blades carried by the shaft, a ring 80 uniting the outer ends of said blades and rotating within the casing, a spiral plate carried by the blades and pitched to create an upward suction, and a substantially horizontal partition carried by the blades and extending from 85 their outer edges adjacent said exit part way toward their inner ends, as and for the purpose set forth.

8. In a grain-separator, the combination with a casing having a plurality of tangential 90 exits, and a main hopper; of an upright shaft journaled through the axis of the casing, upright fan-blades carried by the shaft, a ring uniting the outer ends of said blades and rotating within the casing, a spiral plate carried 95 by the blades and pitched to create an upward suction, the inner convolutions of said spiral plate being lowest and its outer convolutions successively higher and higher, and a partition carried by and cutting through the fan-blades above said spiral plate with its outer edge standing adjacent said outlet, as and for 100 the purpose set forth.

9. In a grain-separator, the combination with a casing having a plurality of tangential 105 exits, partitions between them, and a main hopper; of an upright shaft journaled through the axis of the casing, upright fan-blades carried by the shaft, and a partition cutting through the fan-blades and rotated thereby 110 with its outer edge adjacent the innermost partition at said exit, and means within said outlet for directing the straw upward and outward above said partition and the grain and chaff upward and outward beneath the partition, substantially as described.

10. In a grain-separator, the combination with a casing of inverted conical shape, a cover comprising a ring split radially with its ends sprung so as to produce an exit, partitions 115 producing divisions in this exit, and a fixed hopper carried by said ring; of an upright shaft rotating in the axis of the casing, a spiral plate connected with and rotated by this shaft and pitched to produce upward and out- 120 125 130

ward suction, and a partition also connected with the shaft and rotating in unison with the spiral plate with its outer edge adjacent the inner edge of the innermost partition within 5 said exit.

11. In a grain-separator, the combination with a casing of inverted conical shape, a cover comprising a ring split radially with its ends sprung so as to produce an exit, partitions 10 producing divisions in this exit, and a fixed hopper carried by said ring; of an upright shaft rotating in the axis of the casing, a tubular chaff-hopper carried by the shaft, a spiral plate connected with and rotated by this hopper and pitched to produce upward and outward suction, a partition connected and rotating in unison with the spiral plate with its outer edge adjacent the inner edge of the innermost partition within 15 said exit, and a series of radial tines carried by the chaff-hopper and rotating within the main hopper.
12. In a grain-separator, the combination with a casing of inverted conical shape, a cover comprising a ring split radially with its ends 20 sprung so as to produce an exit, partitions producing divisions in this exit, and a fixed hopper carried by said ring; of an upright shaft rotating in the axis of the casing, a tubular chaff-hopper carried by the shaft, 25 substantially upright fan-blades leading from the chaff-hopper outward, a spiral plate cutting through said blades and pitched to produce upward and outward suction, and a partition 30 rotating in unison with the spiral plate with its outer edge adjacent the inner edge of the innermost partition within said exit.

13. In a grain-separator, the combination with a casing of inverted conical shape, a cover comprising a ring split radially with its ends 35 sprung so as to produce an exit, partitions producing divisions in this exit, and a fixed hopper carried by said ring; of an upright shaft rotating in the axis of the casing, a tubular chaff-hopper carried by the shaft, fan-blades leading tangentially from said chaff-hopper outward, a ring connecting their outer ends, a spiral plate carried by the blades and pitched to produce upward and outward 40 suction, and a partition rotating in unison with the spiral plate with its outer edge adjacent the inner edge of the innermost partition within 45 said exit.
14. In a grain-separator, the combination with a casing of inverted conical shape, a cover 50 comprising a ring split radially with its ends sprung so as to produce an exit, partitions 55 with the spiral plate with its outer edge adjacent the inner edge of the innermost partition within said exit.

15. In a grain-separator, the combination with a casing of inverted conical shape, a cover comprising a ring split radially with its ends sprung so as to produce an exit, partitions 60

producing divisions in this exit, and a fixed hopper carried by said ring; of an upright shaft rotating in the axis of the casing, a tubular chaff-hopper carried by the shaft, a spiral plate connected with and rotated by this hopper and pitched to produce upward and outward suction, a partition rotating in unison with the spiral plate with its outer edge adjacent the inner edge of the innermost partition within 65 said exit, and a series of radial tines carried by the chaff-hopper and rotating within the main hopper.

16. In a grain-separator, the combination with a casing of inverted conical shape, a cover comprising a ring split radially with its ends sprung so as to produce an exit, and a fixed hopper carried by said ring; of an upright shaft rotating in the axis of the casing, a tubular chaff-hopper carried by the shaft, fan-blades leading tangentially from said chaff-hopper outward, a ring connecting their outer ends, and a spiral plate carried by the blades and pitched to produce upward and outward 70 suction.

17. In a grain-separator, the combination with a casing of inverted conical shape, a cover comprising a ring split radially with its ends sprung so as to produce an exit, partitions producing divisions in this exit, and a fixed 75 hopper carried by said ring; of an upright shaft rotating in the axis of the casing, a tubular chaff-hopper carried by the shaft, a spiral plate connected with and rotated by this hopper and pitched to produce upward and outward suction, and a partition rotating in unison with the spiral plate with its outer edge adjacent the inner edge of the innermost partition within 80 said exit.

18. In a grain-separator, the combination with a casing of inverted conical shape, a cover comprising a ring split radially with its ends sprung so as to produce an exit, and a fixed hopper carried by said ring; of an upright shaft rotating in the axis of the casing, a tubular chaff-hopper carried by the shaft, a spiral plate pitched to produce upward and outward 85 suction, and connections between the spiral plate and chaff-hopper.

In testimony whereof I have hereunto subscribed my signature this the 10th day of March, A. D. 1904.

JAMES K. WHITE.
